UNITED STATES PATENT OFFICE.

ROBERT B. CISSEL, OF ELIZABETH, ASSIGNOR, BY DIRECT AND MESNE ASSIGNMENTS, TO THE BACKUS WATER MOTOR COMPANY, OF NEWARK, NEW JERSEY.

ROTARY FAN.

SPECIFICATION forming part of Letters Patent No. 380,788, dated April 10, 1888.

Application filed December 28, 1887. Serial No. 259,925. (No model.)

To all whom it may concern:

Be it known that I, ROBERT B. CISSEL, of Elizabeth, in the county of Union and State of New Jersey, have invented certain new and useful Improvements in Rotary Fans, of which the following is a specification.

This invention relates to an improved clutch device for rotary fans of that class which is used for ventilating and cooling rooms, said 10 clutch device facilitating the locking to or releasing of the fan from the driving-shaft, so as to rotate or stop the same; and the invention consists of a clutch device for rotary fans, which comprises a collar attached to the driving-shaft 15 below the loose hub of the fan, said collar being provided with radial recesses at the under side, lugs applied to a transverse spring-plate that is supported by adjustable sockets of a supporting-frame made integral with the hub, 20 a spindle swiveled to said spring-plate and guided in a bearing at the lower end of the clutch-frame, said spindle being provided with a drip-cup for the oil and a button below said cup. The supporting-sockets of the spring- 25 plate are adjusted in the recesses of the clutch-frame by means of set-screws, so as to set the spring-plate to tension and produce the proper interlocking of the lugs supported on said spring-plate, with the recesses of the collar on the driving-shaft, so as to rotate the fan-hub with said shaft.

In the accompanying drawings, Figures 1 and 2 represent side elevations of my improved clutch device for rotary fans, Fig. 2 being taken 35 at an angle of ninety degrees to the side view shown in Fig. 1. Fig. 3 is a vertical transverse section on line $x-x$, Fig. 2, showing the clutch withdrawn from the collar of the fan-shaft and the fan at rest. Fig. 4 is a horizontal 40 section on line $y-y$, Fig. 2; and Figs. 5 and 6 are a detail bottom view and side view of the fixed collar applied to the driving-shaft.

Similar letters of reference indicate corresponding parts.

45 Referring to the drawings, A represents a driving-shaft, which is suspended in any approved manner by a suitable hanger-frame from the ceiling.

B is a fan-hub, which is placed loosely on the driving-shaft A, and provided with diametrical sockets for the blades of the fan and with inclined intermediate sockets for applying downwardly-extending auxiliary fans.

To the lower end of the driving-shaft A, and below the lower edge of the loose fan-hub B, is rigidly secured a collar, C, which is retained 50 in position on the shaft by a set-screw, d. The collar C is provided at the under side with radial recesses a, which are engaged by lugs b, 55 that are applied to a supporting-ring, b', which is attached by fastening-screws b² to a transverse spring-plate, D, that extends diametrically across the clutch-frame E, said spring-plate being supported in adjustable sockets e 60 e, that are guided in recesses e' of the clutch-frame. The sockets e e are set closer to or farther away from each other by set-screws e², 65 that pass through the clutch-frame E, so as to set the spring-plate to a greater or smaller degree of tension, and cause thereby the reliable 70 interlocking of the lugs b with the recesses a of the fixed collar C. To the center of the spring-plate D and axially in line with the driving-shaft A is swiveled by a headed screw, f, a spindle, F, which turns in central bearings, f', 75 at the lower end of the clutch-frame E, said spindle being provided with a drip-cup, f², and below the same with a button, f³.

The clutch-frame E is formed of four radial arms, g g', of which the arms g support the 80 spring-plate D, while the drums g' are arranged at right angles to the arms g and extended upwardly to the fan-hub B, the clutch-frame E being preferably cast integral with the hub, as shown clearly in Fig. 2. The spring-plate supporting-arms g are connected by a ring-shaped portion, g², which imparts the required degree 85 of strength and stiffness to the clutch-frame. For rotating the fan with the driving-shaft the knob f³ of the spindle is taken hold of and the same lifted, so that the spring-plate D springs into its uppermost position and moves the lugs b into the recesses a of the fixed collar C, whereby the clutch-frame, fan-hub, and fan are carried along with the driving-shaft. By pulling 90 the button of the spindle F in downward 95

direction the spring-plate springs into its lowermost position, as shown in Fig. 3, so as to withdraw the lugs *b* from the recesses of the collar *C* and release thereby the fan-hub from the driving-shaft, so that the latter rotates without taking the fan along. As the spindle *F* is swiveled to the spring-plate, it does not rotate with the clutch-frame when taken hold of, so that the clutch may be operated without difficulty whether the fan is in motion or at rest. The drip-cup of the spindle *F* takes up any waste oil that passes from the journal-bearing of the fan-hub to the lower end of the fan-shaft and prevents it from dripping on the floor. A conveniently-operated and effective clutch device for rotary fans is thus obtained, by which the fans can be quickly thrown in or out of motion, as required.

Having thus described my invention, I claim as new and desire to secure by Letters Patent—

1. The combination, with a driving fan-shaft, a loose fan-hub on the same, a clutch-frame made integral with the fan-hub, a recessed collar applied to the driving-shaft below the fan-

hub, a transverse spring-plate supported by 25 the clutch-frame, lugs attached to the spring-plate and engaging the recesses of the collar, and a spindle swiveled to the spring-plate and guided in bearings of the clutch frame, substantially as set forth.

2. The combination, with a fixed collar at the lower end of the driving-shaft, said collar having recesses at the under side, a clutch-frame, a fan-hub located above the collar and made integral with said fan-hub, a transverse 35 spring-plate, adjustable sockets guided in recesses of the clutch-frame, lugs attached to the spring-plate and engaging the recesses of the collar, and a spindle swiveled to the spring-plate and guided in bearings of the clutch- 40 frame, substantially as set forth.

In testimony that I claim the foregoing as my invention I have signed my name in presence of two subscribing witnesses.

ROBERT B. CISSEL.
